UNITED STATES PATENT OFFICE.

THOMAS K. STAMATSON, OF BROOKLYN, NEW YORK, ASSIGNOR TO KELLER PRINTING COMPANY, OF NEW YORK, N. Y., A CORPORATION OF NEW YORK.

MACHINE FOR PRINTING TICKETS.

Application filed January 10, 1925. Serial No. 1,633.

To all whom it may concern:

Be it known that I, THOMAS K. STAMATSON, a citizen of the United States, and resident of Brooklyn, in the county of Kings and State of New York, have invented certain new and useful Improvements in Machines for Printing Tickets, of which the following is a specification.

This invention relates to machines for printing tickets, and it has particular relation to an improved mechanism for imprinting the "lot numbers" or other identifying data successively upon clothing tickets which are to be attached to garments, or upon other or analogous tickets which are fed through the machine in continuous strips comprising successively the respective ticket units.

The object of my invention is to provide a simple and improved mechanism of the character set forth, which will possess advantages in point of convenience and delicacy of adjustment, positive and effective action, economy in construction and general efficiency.

The present invention relates especially to certain improvements upon the type of machine shown in the Keller Patent No. 1,485,270, of February 26, 1924, whereby control of the conditions of delicate adjustment is more conveniently effected and maintained, and whereby a more perfect adjustment for the printing impression is secured.

In the drawings—

Figure 1 is a side view of a portion of a machine embodying my improvements.

Fig. 2 is a face view of the mechanism shown in Fig. 1.

Fig. 3 is a side view opposite to that shown in Fig. 1.

Fig. 4 is a vertical sectional view on the line 4—4, Fig. 3.

Fig. 12 is a detail perspective view of the adjustable bushing for the inking-roller shaft.

Corresponding parts in all the figures are 60 denoted by the same reference characters.

Referring to the drawings, 16 designates a suitable upright frame which supports in relative position the operative parts herein-after described. Comprised in the usual machine is a main revolute shaft, 17, which carries the printing media and is mounted in projective position from the framework.

Said shaft carries a fixed collar, 18, constituting the hub of a driving gear, 19, and 70 beyond said gear-collar the shaft carries the printing media. The printing media may be of any suitable character and construction, in which the type-heads are located at

the periphery of a printing drum which revolves with said main carrying-shaft, and I have herein illustrated the type of printing media as shown in the previous Keller patent before mentioned, comprising type-discs, 20, formed by a metallic plate and having 80 a circular periphery which at equi-distant points thereon is provided with projective

type-heads, 21, having the characters to be printed. Said type-discs when collectively 75 assembled together successively and side by side in fixed position upon the main shaft, to be carried thereby in its revolution, constitute a printing drum having at each cross

series of type-heads the desired series of characters representing the "lot numbers" 90 or other identifying data to be printed. A platen or bed of any suitable construction, as indicated at 22, is mounted in relative position beneath the printing drum, and the

continuous ticket-strip, shown at 23, is fed 95 in and through the mechanism between the

type-heads 21 and said platen or bed. The latter has a curved periphery and is usually of drum form and revolvably mounted, and the respective cross-series of type-heads 21 of the revolving printing drum contact with and imprint upon the respective spaced units of the continuous ticket-strip 23 at the apex of the successive arcs of the curved periphery of the platen in the revolution thereof, the drum-platen being driven in its movement relative to the printing drum by a gear, shown at 24, suitably comprised in the driving mechanism of the machine and meshing with the gear 19 of the printing media driving-shaft 17 to impart motion to the latter.

The foregoing mechanism, as above described, I have herein shown as substantially the same as that in the before-mentioned Keller patent, though it will be understood that the general machine mechanism and character of printing media may be of any suitable or desired construction adaptable to the conditions of the improved mechanism constituting the present invention and improvements and as hereinafter described.

In machines of the class to which my improvements especially relate, an inking drum or roller, as at 25, is provided and mounted to contact with the type heads 21 of the printing media to supply the ink thereto. Said inking drum is suitably mounted above the printing drum and usually carries a felt ink-pad at its cylindrical surface.

In the operative conditions and service of ticket-printing mechanisms of the class to which my invention is especially directed, it is an important desideratum that a very delicate adjustment of the plane of the type-heads of the printing media be permitted, to compensate for very slight variation in the thickness of the paper ticket-strips which are fed through the mechanism between the printing-heads 21 and the underlying platen or bed, or for wear of the printing characters. In such adjustment the plane of the type-heads is varied by adjustment of the plane of the main carrying-shaft, 17, whereby the peripheral printing characters of the printing media are brought to a position of adjustment towards or from the periphery of the platen or bed 22.

In the before-mentioned Keller patent, an adjustment mechanism for the purpose just stated comprises a bushing member having a cylindrical circumference turnably mounted in a corresponding cylindrical opening in the framework, 16, and having a longitudinal cylindrical bore on a plane eccentric to the center or axis of the bushing in its turnable adjustable movement, through which bore the revoluble main printing-media shaft passes and has its

bearing. Thus, a slight turning movement of the eccentric-bore bearing-bushing would effect a very delicate variation in the plane of the printing-media shaft. In such previous construction, said turnable bushing is locked in adjusted position by a circumferential flange at its inner end, adapted to bear against the inner face of the framework, and an externally-threaded opposite or outer end carrying a lock-nut adapted to seat against the opposite or outer face of the framework.

My present invention is designed to provide improvements not only in the character of an adjustable bearing-bushing for the purpose above stated, but also in the construction for setting and locking or maintaining such bushing in adjusted position, and in the eccentric character of the bushing as a bearing for the printing-media shaft, whereby the conditions of extreme delicacy and convenience in the adjustment action and positive maintenance of the adjusted position will be enhanced and a perfect relationship of the plane of the printing-heads to the surface of the platen will be preserved in the adjustable variation of the plane of the carrying shaft, substantially as hereinafter set forth.

In carrying out the improvements just indicated, the bearing-bushing member has a body portion, 26, which is preferably of disc shape having a flat or plane inner face, 27, and a circular periphery. Said body has a tubular cylindrical extension, 28, projective from its inner face and seated in a corresponding cylindrical seat, 29, in the frame 16, whereby said bushing member is turnably movable in said seat. The bushing member has a longitudinal bore, 30, extending through the body-disc 26 and the cylindrical extension 28 and constituting the bearing for the revoluble printing-media shaft 17, and the cylindrical circumference of said extension 28 is eccentric to the center of said bearing-bore. The bore 30 is in its longitudinal extent preferably in the plane of the center of the bushing body-disc 26 and is eccentric to the cylindrical circumference of the body-extension 28 which is turnably seated in its mounting, said extension being itself eccentric to the center of said body-disc. Thus, when the bushing member is turnably adjusted in its cylindrical seat the plane of the printing-media shaft, and the peripheral printing characters of the printing drum carried thereby, will be varied with relation to the periphery of the impression platen or bed, and afford the desired adjustment for the printing impression as before described.

A tubular extension, as at 31, is also preferably provided projectively from the outer face of the bushing body-disc 26, in line with the center thereof, through which

the bore 30 is extended, to form an extension-bearing for the main printing-media shaft 17. The bushing member is locked in its desired adjusted position and clamped in its seat-mounting with its inner face against the frame-work, by means of set-screws, 32-32, passing through segmental slots, 33-33, in the bushing body-disc 26 at opposite sides of the center thereof, and entering the frame 16. The printing-media shaft 17 is secured in its revoluble mounting in the bore 30 of the eccentric bushing by means of a collar, 34, carried by the shaft at its outer end and bearing against the end 15 of the outer extension 31 of the bushing, said collar co-acting with the fixed gear-hub 18 which bears against the end of the inner extension 28 of the bushing member, and being positioned by means of a set-screw, 35.

20 A very delicate and convenient adjustment of the eccentric bearing-bushing is effected by means of adjusting-screws, 36-36, extending downwardly through the framework and respectively bearing against shoulders, 37-37, formed by recesses, as at 38-38, in the inner face of the bushing body-disc 26, said adjusting-screws and shoulders being respectively at opposite sides of the center or axis of the body-disc of the turnable bushing and the degree of adjustment being limited by the end walls of the respective recesses 38. Thus, by releasing the set-screws 32 and respectively operating the adjusting-screws 36 at 25 opposite sides of the bushing member, the desired delicate degree of adjustment of the latter in its eccentric turnable mounting will be effected, after which the set-screws 32 are again operated to secure and clamp the bushing in its adjusted position. The adjustment action is therefore positively and accurately effected by mechanical screw-action, and not by manual turning of the bushing as is the case with the mechanism of the before-mentioned Keller patent, and any indefinite condition of adjustment by manual turning of the bushing is thus effectively precluded.

30 In the preferred mechanism related to the mounting of the adjusting-screws 36, a supplementary frame-block, 39, is mounted upon the main frame 16 by means of a shoulder-rest, 40, and securing-screws, 41-41, extending through the body of said frame-block beneath said shoulder-rest and at opposite sides and entering the frame 16, the adjusting-screws 36 for the turnable bushing being threaded downwardly through the body of said frame-block. The latter is 35 mounted directly above the circular body-disc 26 of the turnable bushing, and preferably has its under side segmentally curved, as at 42, in an arc corresponding to the circular periphery of the bushing body-disc, and preferably said frame-block

forms the mounting for the shaft of the inking drum, by means of a top extension, 43, having a cylindrical bore, 44, in a plane parallel to the bore in the bushing member.

35 In my present improvements, the inking drum is also mounted to be adjustable in its relationship to the peripheral printing characters of the printing drum, to control the conditions of its inking action thereon and to compensate for the degree of adjustment of the printing drum which is effected by action of the eccentric bearing-bushing for the main shaft 17. In the preferred construction as herein shown, the inking drum 25 is revolvably mounted upon a stationary shaft, 45, and is operated by a gear, 46, meshing with the gear 19 of the main shaft 17, said gear 46 being carried upon a collar, 47, revolvably mounted upon the shaft 45 and carrying the inking drum.

40 To effect the delicate and convenient adjustment of the stationary shaft of the revoluble inking drum, a bushing member similar to that before described with reference to the eccentric mounting of the main printing-media shaft 17 is provided. Said turnable eccentric bushing for the inking drum shaft has a body-disc, 48, the inner face of which bears against the outer face of the top extension 43 of the frame-block 39, and a tubular cylindrical extension, 49, projects from said inner face of said disc-body and is turnably mounted in the cylindrical bore 44 of the frame 43, which bore constitutes a corresponding cylindrical seat for said extension. The extension 49 has its cylindrical circumference eccentric to the center of the bushing body-disc 48, and a cylindrical bore, 50, is provided through said body-disc and its eccentric extension 49, which bore extends longitudinally on the plane of the center of the body-disc 48 and is eccentric to the center or axis of said cylindrical extension in its turnable movement. The stationary inking-drum shaft 45 passes through the bore 50 of the eccentric bushing, and is secured therein by means of a set-screw, 51, passing through the bushing body-disc 48 to contact with the shaft, or by any other suitable securing means. The adjustment of the bushing for the inking-drum shaft is controlled by a set-screw, 52, passing laterally through the frame 43 to engagement with the eccentric bushing-extension 49 which is turnable in its seat in the frame-bore 44. Thus, by releasing the set-screw 52 the eccentric bushing may be turnably adjusted in a delicate desired movement to vary the plane of the shaft 45 carrying the inking drum 25, for the purpose before stated, after which the set-screw may be operated to secure and clamp the bushing in adjusted position.

45 It will be understood that the improved

eccentric bushing for the shaft of the inking drum or roller, as comprised in my present invention and hereinbefore described, is equally adaptable to conditions in which the inking-drum shaft is revolubly mounted and carries the inking drum in its revoluble movement, the shaft being not stationary but mounted and secured to revolve within the eccentric bearing-bushing in like manner to the mounting of the printing-media shaft as herein set forth, or in conditions in which the inking drum operates merely as an "idler" upon a stationary shaft carried by the eccentric adjustable bushing.

15 The operation and advantages of my improvements will be readily understood by those skilled in the art to which my invention appertains. The mechanism is characterized by simplicity in construction, and 20 therefore economy in manufacture, and enables very delicate adjustment for conditions of perfect efficiency, and with maximum certainty and convenience, to control the operative relationship between the 25 printing media and the platen for perfect printing impression, and between the inking drum and printing media for perfect conditions of ink supply.

I do not desire to be understood as limiting myself to the detail features of construction and arrangement as herein shown and described, as it is manifest that variations and modifications therein may be resorted to, in the adaptation of my invention 30 to varying conditions of use, without departing from the spirit and scope of the invention and improvements. I therefore reserve the right to all such variations and modifications as properly fall within the 35 scope of my invention and the terms of the following claims.

Having thus described my invention, I claim and desire to secure by Letters Patent:

1. In a machine of the class described, 45 for printing successively upon the ticket units of a continuous ticket-strip, a revoluble shaft, printing media carried by said shaft and having printing characters operative in the revolution thereof, an impression platen or bed positioned parallel to 50 said revoluble shaft, a framework having a supporting seat, a bushing member having an extension carried by said seat and turnably movable therein and having a longitudinal bore passing through said extension on a plane eccentric to the axis or center thereof in its turnable movement, said printing-media shaft having its revoluble bearing in said bore, a body member comprised in said bushing and carrying said extension, and means 55 carried by the framework and operative upon 60 said body member to effect mechanical adjustment of said turnable eccentric-bore extension, whereby delicate adjustment of the plane of the print- 65

ing-media shaft to compensate for variation in the thickness of the paper ticket-strips passing between the printing media and the platen may be effected by slight movement of said adjustment means to actuate the bushing member in its turnable movement in its seat.

2. In a machine of the class described, for printing successively upon the ticket units of a continuous ticket-strip, a revoluble shaft, printing media carried by said shaft and having printing characters operative in the revolution thereof, an impression platen or bed positioned parallel to said revoluble shaft, a framework having a supporting seat, a bushing member having an extension carried by said seat and turnably movable therein and having a longitudinal bore passing through said extension on a plane eccentric to the axis or center thereof in its turnable movement, said printing-media shaft having its revoluble bearing in said bore, a body member comprised in said bushing and carrying said extension, means carried by the framework and operative upon said body member to effect mechanical adjustment of said turnable eccentric-bore extension, and supplementary means operative to lock the eccentric bushing in the adjusted position which is set by said mechanical adjustment means, whereby delicate adjustment of the plane of the printing-media shaft to compensate for variation in the thickness of the paper ticket-strips passing between the printing media and the platen may be effected by slight movement of said adjustment means to actuate the bushing member in its turnable movement in its seat.

3. In a machine of the class described, for printing successively upon the ticket units of a continuous ticket-strip, a revoluble shaft, printing media carried by said shaft and having printing characters operative in the revolution thereof, an impression platen or bed positioned parallel to said revoluble shaft, a framework having a supporting seat, a bushing member having an extension carried by said seat and turnably movable therein and having a longitudinal bore passing through said extension on a plane eccentric to the axis or center thereof in its turnable movement, said printing-media shaft having its revoluble bearing in said bore, a body member comprised in said bushing and carrying said extension, and means carried by the framework and operative upon said body member to effect mechanical adjustment of said turnable eccentric-bore extension, said adjustment means comprising a set-screw operative to bear upon said body member in a plane at one side the center or axis thereof in its turnable movement, whereby delicate adjustment of the plane of the printing-media shaft to compensate for variation in the thickness of the paper

ticket-strips passing between the printing media and the platen may be effected by slight movement of said adjustment means to actuate the bushing member in its turnable movement in its seat.

4. In a machine of the class described, for printing successively upon the ticket units of a continuous ticket-strip, a revolute shaft, printing media carried by said shaft and having printing characters operative in the revolution thereof, an impression platen or bed positioned parallel to said revolute shaft, a frame work having a supporting seat, a bushing member having an extension carried by said seat and turnably movable therein and having longitudinal bore passing through said extension on a plane eccentric to the axis or center thereof in its turnable movement, said printing-media shaft having its revolute bearing in said bore, a body member comprised in said bushing and carrying said extension and having a segmental slot in a plane at one side the center or axis of said body member in its turnable movement, means carried by the framework and operative upon said body member to effect mechanical adjustment of said turnable eccentric-bore extension; said adjustment means comprising a set-screw operative to bear upon said body member in a plane at one side the center or axis thereof in its turnable movement, and a set-screw operative in said slot to lock the eccentric bushing in the adjusted position which is set by said first-mentioned adjustment screw, whereby delicate adjustment of the plane of the printing-media shaft to compensate for variation in the thickness of the paper ticket-strips passing between the printing media and the platen may be effected by slight movement of said adjustment means to actuate the bushing member in its turnable movement in its seat.

5. In a machine of the class described, for
printing successively upon the ticket units
of a continuous ticket-strip, a revoluble
shaft, printing media carried by said shaft
and having printing characters operative
in the revolution thereof, an impression
platens or bed positioned parallel to said
revoluble shaft, a framework having a sup-
porting seat, a bushing member having an
extension carried by said seat and turnably
movable therein and having a longitudinal
bore passing through said extension on a
plane eccentric to the axis or center thereof
in its turnable movement, said printing-
media shaft having its revoluble bearing in
said bore, a body member comprised in said
bushing and carrying said extension, and
means carried by the framework and oper-
ative upon said body member to effect
mechanical adjustment of said turnable
eccentric-bore extension, said adjustment
means being in a plane respectively at oppo-

site sides of the axis or center of said body member in its turnable invenient, whereby delicate adjustment of the plane of the printing-media shaft to compensate for variation in the thickness of the paper ticket-strips passing between the printing

elict strips passing between the printing media and the platen may be effected by slight movement of said adjustment means to actuate the bushing member in its turnable movement in its seat.

6. In a machine of the class described, for printing successively upon the ticket units of a continuous ticket-strip, a revoluble shaft, printing media carried by said shaft and having printing characters operative in the revolution thereof, an impression platen or bed positioned parallel to said revoluble shaft, a framework having a supporting seat, a bushing member having an extension carried by said seat and turnably movable therein and having a longitudinal bore passing through said extension on a plane eccentric to the axis or center thereof in its turnable movement, said printing-media shaft having its revoluble bearing in said bore, a body member comprised in said bushing and carrying said extension, means carried by the framework and operative upon said body member to effect mechanical adjustment of said turnable eccentric-bore extension, and supplementary means operative to lock the eccentric bushing in the adjusted position.

position which is set by said mechanical adjustment means, said supplementary locking means being respectively at opposite sides of the center or axis of said body member in its turnable movement, whereby delicate adjustment of the platen of the printing-media shaft to compensate for variation in the thickness of the paper ticket-strips passing between the printing media and the platen may be effected by slight movement of said adjustment means to actuate the bushing member in its turnable movement in its seat. 11

7. In a machine of the class described, for printing successively upon the ticket units of a continuous ticket-strip, a revoluble shaft, printing media carried by said shaft and having printing characters operative in the revolution thereof, an impeller, a

the revolution thereof, an impression platen or bed positioned parallel to said revoluble shaft, a framework having a supporting seat, a bushing member having an extension carried by said seat and turnably movable therein and having a longitudinal bore passing through said extension on a plane eccentric to the axis or center thereof in its turnable movement, said printing-media shaft having its revoluble bearing in said bore, a body member comprised in said bushing and carrying said extension, and means carried by the framework and operative upon said body member to effect mechanical adjustment of said turnable eccentric-bore 13

extension, said adjustment means comprising set-screws operative to bear upon said body member respectively in a plane at opposite sides of the center or axis thereof in 5 its turnable movement, whereby delicate adjustment of the plane of the printing-media shaft to compensate for variation in the thickness of the paper ticket-strips passing between the printing media and the 10 platen may be effected by slight movement of said adjustment means to actuate the bushing member in its turnable movement in its seat.

8. In a machine of the class described, for 15 printing successively upon the ticket units of a continuous ticket-strip, a revoluble shaft, printing media carried by said shaft and having printing characters operative in the revolution thereof, an impression platen or 20 bed positioned parallel to said revoluble shaft, a framework having a supporting seat, a bushing member having an extension carried by said seat and turnably movable therein and having a longitudinal bore passing 25 through said extension on a plane eccentric to the axis or center thereof in its turnable movement, said printing-media shaft having its revoluble bearing in said bore, a body member comprised in said bushing and carrying 30 said extension and having segmental slots respectively at opposite sides of the center or axis of said body member in its turnable movement, means carried by the framework and operative upon said body 35 member to effect mechanical adjustment of said turnable eccentric-bore extension, said adjustment means comprising set-screws operative to bear upon said body member respectively in a plane at opposite sides of the center or axis thereof in its turnable movement, and set-screws operative in said opposite slots to lock the eccentric bushing in the 40 adjusted position which is set by said first-mentioned adjustment screws, whereby delicate adjustment of the plane of the printing-media shaft to compensate for variation in the thickness of the paper ticket-strips passing between the printing media and the 45 platen may be effected by slight movement of said adjustment means to actuate the bushing member in its turnable movement in its seat.

9. In a machine of the class described, for 55 printing successively upon the ticket units of a continuous ticket-strip, a revoluble shaft, printing media carried by said shaft and having printing characters operative in the revolution thereof, an impression platen or bed positioned parallel to said revoluble shaft, a framework having a supporting seat, a bushing member having an extension carried by said seat and turnably movable therein and having a longitudinal bore passing 60 through said extension on a plane eccentric to the axis or center thereof in its turn-

able movement, said printing-media shaft having its revoluble bearing in said bore, a body member comprised in said bushing and carrying said extension and having a shoulder in a plane at one side the center or axis 70 of said body member in its turnable movement, and a set-screw carried by the framework and operative upon said shoulder of said body member to effect mechanical adjustment of said turnable eccentric-bore extension, whereby delicate adjustment of the plane of the printing-media shaft to compensate for variation in the thickness of the paper ticket-strips passing between the printing media and the platen may be effected by 80 slight movement of said adjustment means to actuate the bushing member in its turnable movement in its seat.

10. In a machine of the class described, for 85 printing successively upon the ticket units of a continuous ticket-strip, a revoluble shaft, printing media carried by said shaft and having printing characters operative in the revolution thereof, an impression platen or bed positioned parallel to said revoluble 90 shaft, a framework having a supporting seat, a bushing member having an extension carried by said seat and turnably movable therein and having a longitudinal bore passing through said extension on a plane eccentric to the axis or center thereof in its turnable movement, said printing-media shaft having its revoluble bearing in said bore, a body member comprised in said bushing and carrying 95 said extension and having shoulders respectively in a plane at opposite sides the center or axis of said body member in its turnable movement, and set-screws carried by the framework and respectively operative upon said opposite shoulders of said body member to effect mechanical adjustment of said turnable eccentric-bore extension, whereby delicate adjustment of the plane of the printing-media shaft to 100 compensate for variation in the thickness of the paper ticket-strips passing between the printing media and the platen may be effected by slight movement of said adjustment means to actuate the bushing member in its turnable movement in its seat.

11. In a machine of the class described, comprising a revoluble shaft carrying printing media having printing characters operative in the revolution of said shaft, an impression platen or bed positioned parallel to said revoluble shaft, and a framework having a cylindrical supporting seat, an eccentric bushing-member comprising a body disc having at its inner face a cylindrical extension carried by said seat and turnably movable therein, said bushing member having a cylindrical bore extending through said body disc and said extension on a plane eccentric to the cylindrical circumference of said extension and constituting the revoluble bear- 120 125 130

ing for said printing-media shaft, and means bearing directly upon said body disc to effect mechanical adjustment thereof in its axial turnable movement, whereby delicate 5 adjustment of the plane of the printing-media shaft may be effected by actuation of said adjustment means to move the bushing member turnably in its seat.

12. In a machine of the class described, 10 comprising a revoluble shaft carrying printing media having printing characters operative in the revolution of said shaft, an impression platen or bed positioned parallel to said revoluble shaft, and a framework 15 having a cylindrical supporting seat, an eccentric bushing-member comprising a body disc having at its inner face a cylindrical extension carried by said seat and turnably movable therein, said bushing member having a cylindrical bore extending through said body disc and said extension on a plane eccentric to the cylindrical circumference of said extension and constituting the revoluble bearing for said printing-media 20 shaft, and said body disc having shoulders in a plane at opposite sides of its center or axis, and means engaging said shoulders to effect mechanical adjustment of said body disc in its axial turnable movement, whereby 25 delicate adjustment of the plane of the printing-media shaft may be effected by actuation of said adjustment means to move the bushing member turnably in its seat.

13. In a machine of the class described, 30 comprising a revoluble shaft carrying printing media having printing characters operative in the revolution of said shaft, an impression platen or bed positioned parallel to said revoluble shaft, and a framework 35 having a cylindrical supporting seat, an eccentric bushing-member comprising a body disc having at its inner face a cylindrical extension carried by said seat and turnably movable therein, said bushing member having shoulders in a plane at opposite sides of its center or axis and segmental slots in a plane concentric to the center or axis, means engaging said shoulders to effect mechanical adjustment of said body disc in its 40 axial turnable movement, and means engaging said slots to lock the adjusted position which is set by said mechanical adjustment means, whereby delicate adjustment of the plane of the printing-media shaft may be effected by actuation of said adjustment means to move the bushing member turnably in its seat.

14. In a machine of the class described, 45 comprising a revoluble shaft carrying printing media having printing characters operative in the revolution of said shaft, an impression platen or bed positioned parallel to said revoluble shaft, and a framework having a cylindrical supporting seat, an eccentric bushing-member comprising a body

disc having at its inner face a cylindrical extension eccentric to the center or axis of the body disc and turnably carried by said seat, said bushing member having a cylindrical bore extending through said body disc and said extension in a continuous longitudinal plane concentric to the axis of the body disc and eccentric to the cylindrical circumference of said eccentrically-carried extension, said printing-media shaft 70 having its revoluble bearing in said bore, and means bearing directly upon said body disc to effect mechanical adjustment thereof in its axial turnable movement, whereby delicate 75 adjustment of the plane of the printing-media shaft may be effected by actuation of said adjustment means to move the bushing member turnably in its seat.

15. In a machine of the class described, 80 comprising a revoluble shaft carrying printing media having printing characters operative in the revolution of said shaft, an impression platen or bed positioned parallel to said revoluble shaft, and a framework 85 having a cylindrical supporting seat, an eccentric bushing-member comprising a body disc having at its inner face a cylindrical extension eccentric to the center or axis of the body disc and turnably carried by said seat, said bushing member having a cylindrical 90 bore extending through said body disc and said extension in a continuous longitudinal plane concentric to the axis of the body disc and eccentric to the cylindrical circumference of said eccentrically-carried extension and constituting the revoluble bearing for said printing-media shaft, and said body disc 95 having shoulders in a plane at opposite sides of its center or axis, and means engaging said shoulders to effect mechanical adjustment of the bushing member in its axial turnable movement, whereby delicate adjustment of the plane of the printing-media shaft may be effected by actuation of said adjustment means to move the bushing member turnably in its seat.

16. In a machine of the class described, 100 comprising a revoluble shaft carrying printing media having printing characters operative in the revolution of said shaft, an impression platen or bed positioned parallel to said revoluble shaft, and a framework having a cylindrical supporting seat, an eccentric bushing-member comprising a body disc having at its inner face a cylindrical extension eccentric to the center or axis of the body disc and turnably carried by said seat, said bushing member having a cylindrical bore extending through said body disc and said extension in a continuous longitudinal 105 plane concentric to the axis of the body disc and eccentric to the cylindrical circumference of said eccentrically-carried extension and constituting the revoluble bearing for said printing-media shaft, and said body 110 disc having at its inner face a cylindrical extension eccentric to the center or axis of the body disc and turnably carried by said seat, said bushing member having a cylindrical bore extending through said body disc and said extension in a continuous longitudinal plane concentric to the axis of the body disc and eccentric to the cylindrical circumference of said eccentrically-carried extension and constituting the revoluble bearing for said printing-media shaft, and said body 115 disc having at its inner face a cylindrical extension eccentric to the center or axis of the body disc and turnably carried by said seat, said bushing member having a cylindrical bore extending through said body disc and said extension in a continuous longitudinal plane concentric to the axis of the body disc and eccentric to the cylindrical circumference of said eccentrically-carried extension and constituting the revoluble bearing for said printing-media shaft, and said body 120 disc having at its inner face a cylindrical extension eccentric to the center or axis of the body disc and turnably carried by said seat, said bushing member having a cylindrical bore extending through said body disc and said extension in a continuous longitudinal plane concentric to the axis of the body disc and eccentric to the cylindrical circumference of said eccentrically-carried extension and constituting the revoluble bearing for said printing-media shaft, and said body 125 disc having at its inner face a cylindrical extension eccentric to the center or axis of the body disc and turnably carried by said seat, said bushing member having a cylindrical bore extending through said body disc and said extension in a continuous longitudinal plane concentric to the axis of the body disc and eccentric to the cylindrical circumference of said eccentrically-carried extension and constituting the revoluble bearing for said printing-media shaft, and said body 130 disc having at its inner face a cylindrical extension eccentric to the center or axis of the body disc and turnably carried by said seat, said bushing member having a cylindrical bore extending through said body disc and said extension in a continuous longitudinal plane concentric to the axis of the body disc and eccentric to the cylindrical circumference of said eccentrically-carried extension and constituting the revoluble bearing for said printing-media shaft, and said body

- disc having shoulders in a plane at opposite sides of its center or axis and segmental slots concentric to said axis, means engaging said shoulders to effect mechanical adjustment of the bushing member in its axial turnable movement, and means engaging said slots to lock the adjusted position which is set by said mechanical adjustment means, whereby delicate adjustment of the plane of the printing-media shaft may be effected by actuation of said adjustment means to move the bushing member turnably in its seat.
17. In a machine of the class described, comprising a revoluble shaft carrying printing media having printing characters operative in the revolution of said shaft, a framework having a supporting seat, a bushing member carried by said seat and turnably movable therein and having a longitudinal bore on a plane eccentric to the axis or center of the bushing in its turnable movement, means carried by the framework and engaging said bushing laterally to lock the same in the adjusted position of its turnable movement, a shaft carried by said bore, and an inking drum or roller carried by said last-mentioned shaft in contact relation to the printing characters carried by said first-mentioned shaft, whereby delicate adjustment of the plane of the inking drum to vary its contact relation to the printing characters may be effected by slight movement of the turnable eccentric-bushing which carries the inking-drum shaft.
18. In a machine of the class described, comprising a revoluble shaft carrying printing media having printing characters operative in the revolution of said shaft, a framework having a supporting seat, a bushing member having an extension carried by said seat and turnably movable therein, a body member comprised in said bushing and carrying said extension, a longitudinal bore passing through said body member and through said extension on a plane eccentric to the center or axis thereof in its turnable movement, means for locking said bushing in the adjusted position of its turnable movement, a shaft carried by said bore and extending through said body member and eccentric extension and having a fixed connection with said body member of the bushing, and an inking drum or roller revolvably carried by said last-mentioned shaft in contact relation to the printing characters carried by said first-mentioned shaft, whereby delicate adjustment of the plane of the inking drum to vary its contact relation to the printing characters may be effected by slight movement of the turnable eccentric-bushing which carries the inking-drum shaft.
19. In a machine of the class described, comprising a revoluble shaft carrying printing media having printing characters opera-
- tive in the revolution of said shaft, a framework having a supporting seat, a bushing member having an extension carried by said seat and turnably movable therein, a body member comprised in said bushing and carrying said extension, a longitudinal bore passing through said body member and through said extension on a plane eccentric to the center or axis thereof in its turnable movement, means carried by the framework and engaging said eccentric extension laterally to lock the bushing member in the adjusted position of its turnable movement, a shaft carried by said bore and extending through said body member and eccentric extension and having a fixed connection with said body member of the bushing, and an inking drum or roller revolvably carried by said last-mentioned shaft in contact relation to the printing characters carried by said first-mentioned shaft, whereby delicate adjustment of the plane of the inking drum to vary its contact relation to the printing characters may be effected by slight movement of the turnable eccentric-bushing which carries the inking-drum shaft.
20. In a machine of the class described, comprising a revoluble shaft carrying printing media having printing characters operative in the revolution of said shaft, a framework having a cylindrical supporting seat, an eccentric bushing member comprising a body disc having at its inner face a cylindrical extension eccentric to the center or axis of the body disc and turnably carried by said seat, said bushing member having a bore extending through said body disc and said extension in a continuous longitudinal plane concentric to the axis of the body disc and eccentric to the cylindrical circumference of said eccentrically-carried extension, means for locking said eccentric extension in the adjusted position of its turnable movement, a shaft carried by said bore, and an inking drum or roller carried by said last-mentioned shaft in contact relation to the printing characters carried by said first-mentioned shaft, whereby delicate adjustment of the plane of the inking drum to vary its contact relation to the printing characters may be effected by slight movement of the turnable eccentric-bushing which carries the inking-drum shaft.
21. In a machine of the class described, comprising a revoluble shaft carrying printing media having printing characters operative in the revolution of said shaft, a framework having a cylindrical supporting seat, an eccentric bushing member comprising a body or head having at its inner face a cylindrical extension carried by said seat and turnably movable therein, said bushing member having a bore extending through said body and said extension on a plane ee-

centric to the cylindrical circumference of said extension, and said body or head having means for engaging a shaft fixed in said bore, means for locking said eccentric extension in the adjusted position of its turnable movement, a shaft carried in fixed position in said bore, and an inking drum or roller revolvably carried by said last-mentioned shaft in contact relation to the printing characters carried by said first-mentioned

shaft, whereby delicate adjustment of the plane of the revoluble inking drum to vary its contact relation to the printing characters may be effected by slight movement of the turnable eccentric-bushing which carries the stationary inking-drum shaft. 15

In testimony whereof I have signed the foregoing specification.

THOMAS K. STAMATSON.
